SUPPORTING BRACKET

Fritiof E. Olson, Wellesley, Mass.

Application April 22, 1954, Serial No. 424,919

1 Claim. (Cl. 15—268)

The present invention relates to a supporting bracket for adjustable attachment to a longitudinal element such as one or both of the upright rails of a ladder.

One or two pairs of brackets of the present invention may be used and they are attached to the side rails of a ladder or they may be attached to two separate rails, such as two two by fours, spaced apart and supported in generally vertical or upright position by leaning them against a wall. For convenience the upright members to which the brackets are attached are called rails or side rails hereafter. The brackets may be adjusted to any desired height above the ground and they are particularly useful to support storm sashes, screens, blinds and the like, for painting or cleaning. When two pairs are used the lower pair support the article being painted or cleaned while the top pair may be used either to prevent the article from tipping out of the lower pair or to space the upper portion of the article forwardly from the uprights to prevent marring or running of paint applied to the article.

In another embodiment of the present invention a single bracket is secured between the two uprights or rails.

Brackets embodying the present invention are simple to attach to the side rails of an ordinary ladder or step ladder and they grip the side rails firmly and provide a solid support for the article to be painted or cleaned. They are simple and sturdy in construction, small in size so that they require little storage space and are handy to carry around to various jobs. They facilitate the work of cleaning or painting sashes, screens, blinds or the like by adapting any common type of ladder to support the work in a convenient working position.

They are also economical to manufacture and easy to assemble.

Further objects and advantages of the present invention will be apparent from the following description and accompanying drawings, in which:

Fig. 1 is a perspective view partly in phantom illustrating one embodiment of the bracket of the present invention attached to the side rail of a ladder;

Fig. 2 is a perspective view partially in phantom looking at the embodiment of Fig. 1 from the opposite side and with some of the parts of the bracket removed;

Fig. 3 is a top plan view of the bracket of Fig. 1 showing it attached to a side rail of a ladder which is shown in section;

Fig. 4 is a partial front elevation illustrating one arrangement of the brackets of Fig. 1 on the two side rails of a ladder and supporting a sash which is shown in phantom;

Fig. 5 is a section on the lines 5—5 of Fig. 4;

Fig. 6 is a partial front elevation showing another arrangement of the top pair of brackets of Fig. 1 arranged to space the top portion of a sash forwardly from the side rails of a ladder;

Fig. 7 is a side elevation looking from left to right at Fig. 6;

Fig. 8 is a top plan view of another embodiment of

bracket of the present invention showing it attached to the side rails of a ladder which is shown in phantom;

Fig. 9 is a front elevation of the embodiment of Fig. 8;

Fig. 10 is an end elevation looking from left to right

at Fig. 9; and

Fig. 11 is a section on the lines 11—11 of Fig. 8.

Referring to Figs. 1 to 5 of the drawings, the bracket indicated generally by the numeral 10 comprises a sheet metal member 11 and the rod 12.

10 The main body sheet metal member 11 is provided with a pair of substantially vertical flanges 17 which extend substantially at right angles to the member 11 adjacent to the rear thereof and when the bracket is set up for use the faces 14a of these flanges may abut or engage the front side 15a of the side rail 15 of a ladder. The side rail 15 is rectangular in cross section with faces 15a and 15c at the front and back respectively and 15b and 15d at the sides. The rungs of the ladder are indicated at 13. It will be appreciated that the brackets of the present invention may be used equally well with any pair of longitudinal upright elements, for example, a pair of two by fours leaning against the side of a building.

20 The corners 16 of the flanges 17 are bent over and provide sharp projections extending rearwardly from the faces 14a and these projections dig into the adjacent side 15a of the side rail 15 and prevent relative movement of the faces 14a and the side 15a when the bracket 10 is attached for use.

25 At the top and bottom of the main body member 11 the substantially horizontal flanges 18 and 19 are bent substantially at right angles to said member and the face 18a of the flange 18 provides the support for the weight of the sash 33 (Figs. 4 and 5). The flanges 27 form sloped walls at the rear of the support faces 18a and 19a.

30 Parallel flanges 21 and 22 are provided at the forward and rear ends of the main body member 11 and they extend substantially at right angles thereto. The transverse perforations 23 and 24 slidably receive the rod 12. 40 The portion 25 of the main body member 11 extends rearwardly of the face 14a and it serves as a guide by abutting the side 15b of the side piece 15 (see Figs. 2 and 3).

45 The rear end of the rod 12 is bent at substantially a right angle to form a hook 26 which engages the rear side 15c of the rail 15 to detachably secure the bracket 10 to the rail 15. The inner surface of the hook 26 is roughened as by screw threading in order to provide a roughened gripping surface toward the side 15c.

50 One end of the rod 12 extends forwardly of the flange 21 and is screw threaded as shown. A wing nut 28 is interiorly threaded for engagement with the screw threads of the rod. By tightening the wing nut 28 the rod 12 is slid forwardly through the perforations 23 and 24 and this causes the hook 26 to move toward the flange 17 so that the rail 15 is gripped between the hook and the flanges 17, thus firmly securing the supporting flange 18 to the rail 15 in proper position to support the bottom of a window or other object. If the faces 14a of the flanges 17 are provided with prongs 16, they are forced into the sides 15a of the rail by the same operation.

55 A metal strap member 29 is pivotally mounted adjacent to the front of the flange 21 by extending the rod 12 through the perforation 30 in the strap member so that it is carried on the rod 12 between the flange 21 and the washer 31 rearwardly of the wing nut 28. The ends of the strap member 29 are made long enough to extend beyond the faces 18a and 19a of the flanges 18 and 19 and they form abutments at the forward ends of the faces 18a and 19a when the strap member is adjusted to the substantially vertical position shown in Figs. 4 and 5 and the wing nut is tightened to hold the strap

member in that position. As shown, the ends of the strap member 29 are bent to provide loops 32.

Figs. 4 and 5 show a storm sash 33 supported by the brackets 10 and while the subsequent description will be with particular reference to such a sash, it will be understood that the article supported by the brackets 10 is not material to the present invention and the brackets may be used to support any object without departing from the spirit of the present invention.

In use the supporting faces 18a of the bottom pair of brackets 10 are first secured to the side rails 15 of the ladder so that the sash will be supported at a convenient height as shown in Figs. 4 and 5. The strap members 29 of the bottom pair of brackets are then rotated and secured in their vertical positions to later prevent the bottom edge 34 of the sash from being jarred forwardly from the faces 18a. The handle 35 of a paint bucket 36 may be supported from one of the loops 32 if desired.

An upper pair of brackets 10 is then attached to the side rails 15 of the ladder at positions so that they will be above the upper edge 37 of the sash 33 and so that the upper edge of the sash will be closely adjacent the lower faces 19a of the flanges 19. The sash 33 is then positioned on the flanges 18 of the lower brackets and the upper edge 37 rests against the flanges 27 which space the upper end of the sash forwardly of the side rails of the ladder. The upper strap members 29 are then rotated to the vertical positions shown and the upper wing nuts are further tightened to securely hold them in such positions. They now extend below the upper edge 37 of the sash and they prevent the sash from tipping or blowing forwardly and thus falling away from the lower pair of brackets.

To remove the sash it is merely necessary to loosen the upper wing nuts sufficiently so that the upper strap members may be rotated to horizontal positions.

Figs. 6 and 7 show the top pair of brackets arranged in a different manner so as to space the top edge 37 of the sash away from all surfaces (in Figs. 4 and 5 it engages the surfaces of the flanges 27). In this way the front and back faces of the sash may be painted and they will not be marred by engagement with any surface while drying. For this purpose the top pair of brackets 10 are attached lower down on the side rails of the ladder than in Figs. 4 and 5 and with the faces 14a of the flanges 17 toward the outer sides 15b of the respective side rails 15 of the ladder. Thus, the main body portions 11 of the top brackets extend laterally from the sides of the ladder as shown in Fig. 6. The strap members 29 are rotated to positions in which one end of each strap member projects forwardly from the main body portion 11 and engages a pane of glass as shown in Fig. 7. The bottom edge 34 of the sash 33 is still supported by a lower pair of brackets as before, but at the top portion of the sash the panes of glass 39 in the sash rest against ends of the strap members 29 and the wooden portions of the sash are thus located forwardly of all surfaces.

In Figs. 8, 9, 10 and 11, a second embodiment 10a of the bracket is shown. It comprises a supporting member 111 which is attached to both side rails 15 of a ladder by a pair of rods 12. The rods 12 and associated parts which attach the bracket 10a to the side rails 15 are substantially the same structurally and functionally as in the first embodiment. In this instance the supporting member 111 is a long piece of sheet metal formed to have an inverted U-shaped cross section with a vertical flange 114 at the rear and a vertical flange 121 at the front. The rods 12 are slidably supported in the transverse perforations 123 and 124. A plurality of laterally spaced perforations 123 and 124 are provided so that the rods 12 may be spaced apart different distances to

accommodate ladders of different widths and also so that the bracket may be located at different elevations on a ladder, the side rails of which converge from bottom to top as is customary.

The top surface of the engagement member 111 is provided with spaced ridges 118 and the bottom of the sash rests upon these ridges. Tabs 127 are bent upwardly from the top surface of the supporting member 111 and they provide walls above the level of the supporting ridges 118 at the rear of the supporting member 111. The tabs 129 are struck up at the front to provide front walls. The tabs 129 at the front function as the latch members 29 of the first embodiment to hold the bottom of the sash against forward displacement.

The flange 114 provides the engagement portion 114a which engages the side 15a of the side rails 15 of a ladder and cooperates with the hooks 26 to grip the side rails 15 when the wing nuts 28 are tightened causing the rods 12 to slide forwardly relative to the flanges 114 and 121.

The tab 132 is struck out of the front flange 121 in the shape of a loop to support the handle 35 of a bucket 36.

It will be appreciated that the above description is of two preferred embodiments of brackets of the present invention and that the substitution of equivalent elements may be made therein without departing from the spirit of the present invention, the scope of which is set forth in the following claim.

I claim:

A supporting bracket for attachment to an upright rail at any selected point therealong comprising a body member having a substantially vertical engagement member at its rearward side for engaging the forward face of such a rail, a substantially horizontal, forwardly extending, substantially flat supporting member, the surface of which is substantially horizontal and substantially perpendicular to the rearward side of said engagement member and a substantially vertical rod mounting member substantially parallel to said engagement member, projecting laterally thereof and having a transverse passage formed therein, the axis of said passage being offset laterally from the engagement portion of the engagement member, a rod slidably mounted in said passage with its longitudinal axis substantially perpendicular to said rod mounting member, whereby a portion of said rod, without passing through the rail, extends rearwardly from a point adjacent to one side of the engagement portion of said engagement member and along a side face of the rail when the forward face of the rail is engaged by said engagement portion, a hook on the rearward portion of said rod extending at an angle thereto for engaging the rearward face of the rail, and means engageable with the forward end of said rod for slidably moving said rod through said passage and for causing said engagement portion and said hook portion to grip said rail therebetween.
